UNITED STATES PATENT OFFICE.

HENRY J. RITTER, OF TIPPECANOE CITY, OHIO.

DESIGN FOR A SWING-FRAME.

SPECIFICATION forming part of Design No. 35,224, dated October 22, 1901.

Application filed September 23, 1901. Serial No. 76,303. Term of patent 7 years.

To all whom it may concern:

Be it known that I, HENRY J. RITTER, a citizen of the United States, residing at Tippecanoe City, in the county of Miami and State 5 of Ohio, have invented and produced a new and original Design for a Swing-Frame, of which the following is a specification, reference being had to the accompanying drawings, wherein—

o Figure 1 is a plan view of a swing-frame embodying my design. Fig. 2 is an end elevation of the same, and Fig. 3 is a side elevation.

As shown in the drawings, the leading or 5 material feature of my design consists of a rectangular base from each side of which a rectangular frame extends upward, said frames being of less width than the length of the sides and being inclined toward each other, o in conjunction with inclined members extending from the tops of these frames to the corners of the base and other inclined members extending from the first-named inclined members in a divergent direction therefrom 5 to the ends of the base.

In the said drawings, 1 indicates the rec-

tangular base, composed of the end members 2 and side members 3. From each side member arises a rectangular frame 4, of less width than the length of the side member and composed of a top piece 5 and side pieces 6. These two upwardly-extending frames are inclined toward each other, as shown in Figs. 1 and 2. From the top of each upright frame there extend to the adjacent corners of the rectangular base 1 inclined members 7, and from a point about half-way up each of the inclined members 7 there extends to the adjacent end piece 2 of the base 1 a divergent member 8.

Having thus fully described my invention, 40 what I claim as new, and desire to secure by Letters Patent, is—

The design for a swing-frame, as herein shown and described.

In testimony whereof I have signed my 45 name to this specification in the presence of two subscribing witnesses.

HENRY J. RITTER.
